ROLLER UNIT

Arthur W. Du Perret, St. Louis County, Mo., assignor to Automatic Devices, Incorporated, St. Louis, Mo., a corporation of Missouri

Application February 28, 1946, Serial No. 650,820

2 Claims. (Cl. 193—42)

1

This invention relates to rollers and more particularly to a roller construction and mounting thereof to produce a unitary structure.

One of the objects of my invention is to produce a single roller unit which can be employed in an efficient manner to accomplish easy moving of various types of articles.

Another object is to produce a roller unit which is simple in design and sturdy in construction.

Yet another object is to produce a roller unit which can be employed individually or with other like units for conveying lengthy articles.

A further object is to provide a roller mounting structure which will permit ready adjustment of the roller so that it can be used to efficiently move and guide articles having widths narrower than the roller length or to move, without guiding, articles having widths greater than the roller length.

Other objects of the invention will become apparent from the following description taken in connection with the accompanying drawings in which:

Figure 1 is a perspective view of a roller unit embodying my invention;

Figure 2 is a top view of the roller unit;

Figure 3 is a side view of the said roller unit; and

Figure 4 is a cross-sectional view taken on the line 4—4 of Figure 3.

Referring to the figures in detail, the roller unit disclosed has a base plate 1 provided at its ends with roller supports 2 and 3. The base plate and the end supports are made from a single plate of steel or other suitable material and the supports constitute flanges turned at right angles to the plane of the base plate. The end support or flange 2 has two holes 4 and 5 therethrough in vertical arrangement and similarly arranged holes 6 and 7 are provided in the end support or flange 3. The roller of the unit comprises a hollow cylindrical member 8 which is arranged to be rotatably mounted on an axle 9. This axle 9 is supported in the holes of the supports or flanges 2 and 3 and may be positioned in either the lower holes 4 and 6 of the flanges or the upper holes 5 and 7. Any suitable bearing structure may be employed for rotatably mounting the roller 8 on the axle. The bearing structure shown comprises flanged roller bearings 10 and 11 inserted in the ends of the cylindrical roller member.

When the axle 9 is positioned in the two lower holes 4 and 6 the roller will lie below the outer edges 12 and 13 of the supports or flanges 2 and

2

3 and thus the upper portions of these flanges will constitute guides for holding any article which is to be moved on the roller from slipping off the ends of said roller. When the axle is placed in the upper holes 5 and 7, then the roller will have an exposed surface above the top edges 12 and 13 of the flanges. When the roller is so mounted the flanges will no longer act as guides and it is thus possible to move over the roller an article which has a greater width than the length of the roller.

The flanges 2 and 3 are each formed to be in the shape of a half of an octagon and the marginal portions at the angular edges on opposite sides of the top edge 12 of the flange 2 are flared outwardly to provide wings indicated at 14 and 15. In a similar manner the marginal portions at the angular edges on opposite sides of the top edge 13 of the flange 3 are flared outwardly to provide wing portions indicated at 16 and 17. With this arrangement it is seen that there will be less likelihood of any material which is passed over the roller when the roller is in its lowermost position from hitting the flanges 2 and 3. The particular flaring arrangement of the flanges is also very beneficial in aiding guiding when a plurality of roller units are arranged at spaced intervals to form a conveyor along which lengthy articles can be conveyed, such as rods, pipes, beams and the like.

30 The roller unit is also so constructed as to be capable of being firmly secured to a floor or some other surface or member. To accomplish this the base plate 1 is provided with holes 18, 19, 20 and 21 at its four corners so that bolts or lag screws may be employed to accomplish the securing. Also, in order to aid in firmly securing the roller unit and to additionally prevent shifting of the roller unit in the event that it is not bolted or screwed down, the marginal portions 22 and 23 adjacent the longitudinal edges of the base plate are turned or pinched in a direction away from the extending flanges to thus form relatively sharp ridges 24 and 25 which can engage a surface and thus assist in preventing shifting of the roller unit. If the surface engaged should be of wood and the roller unit is secured thereto by bolts or screws, these ridges will be caused to be forced into the wood and thus aid in firmly holding the roller unit from shifting.

In order that the axle 9 for the roller may be held in either of its desired positions, and yet be easily removable from the supports or flanges 2 and 3, its ends are provided with holes in which can be inserted cotter pins 26 as shown. Thus

by removing one of the cotter pins the axle can be pulled out of the holes of the flanges and the roller and moved to the other holes.

The roller unit has an innumerable number of uses. A single unit can be placed on the back end of a truck or like place to assist in unloading or moving heavy, lengthy articles. A single unit can also be mounted to serve as an idler for a flexible cable or rope when it is necessary that the cable or rope has to pass over an obstruction, a wall or a window sill. Another use for a single unit would be as a dolly. When it is so used the axle is mounted in the upper holes 5 and 7 so that the surface of the roller is above the flanges 2 and 3. The unit is then turned upside down from the position shown in Figure 1 so that the article to be moved rests upon the bottom surface of the base plate and the roller rests on a floor or like surface. The article can then be pushed and it will roll along the floor in somewhat the same manner as a caster. It will be found superior to just plain rollers since it is not necessary to keep replacing rollers under the article being moved. If it is desired to make a conveyor for lengthy articles from a plurality of rollers, the roller units will be positioned in spaced aligned relation with their axes parallel to each other. The article to be moved can then be pushed down the line of roller units. If the lengthy article is of narrower width than the width of the roller, the axle thereof should be placed in the lower holes 4 and 6 so that the flanges 2 and 3 can act as guides. If the article being moved is wider than the length of the roller, then the axle should be placed in the upper holes 5 and 1. Other uses of the roller unit will readily suggest themselves.

Being aware of the possibility of modification of the structure shown and described without departing from the fundamental principles of my invention, I do not intend that the scope of the invention be limited in any manner except in accordance with the appended claims.

What is claimed is:

1. In a roller unit, a base plate having integral flanges extending at right angles from the ends thereof, the marginal portions adjacent the longitudinal edges of the base plate being turned in a direction away from the flanges to provide side ridges extending beyond the surface of the base plate, said base plate also being provided with holes for receiving attaching means to secure the base plate to another member and cause the ridges to be forced against or into said other member, and a roller supported at its ends in the flanges and arranged for free rotation about

its axis, said end flanges each having outwardly flared wing portions on opposite sides of the axis of the roller and said roller being mounted to have all of its circumferential surface below the plane of the outer edges in order that said flanges can act as guides for a member moved over the roller.

2. In a roller unit, a base plate having integral flanges extending at right angles from the ends thereof, the marginal portions adjacent the longitudinal edges of the base plate being turned in a direction away from the flanges to provide side ridges positioned beyond the surface of the base plate, said base plate also being provided with holes for receiving attaching means to secure the base plate to another member and force the ridges against or into said other member, and each end flange having vertically spaced openings therein, an axle arranged to have its ends positioned in companion openings at equal distances from the base plate, and a cylindrical member journaled on the axle, the axle receiving openings closest to the base plate being so positioned that when the axle is positioned therein the roller will be within the outer ends of the flanges and the axle receiving opening farthest from the base plate being so positioned that when the axle is positioned therein a portion of the roller will be outside the outer ends of the flanges.

ARTHUR W. DU PERRET.
